JOHN C. McLAUGHLIN, OF JERSEY CITY, NEW JERSEY, ASSIGNOR TO UNDERWOOD
TYPEWRITER COMPANY, OF NEW YORK, N. Y., A CORPORATION OF DELAWARE.

TYPE-WRITING MACHINE.

1,065,826.

Specification of Letters Patent. Patented June 24, 1913.

Application filed October 17, 1911. Serial No. 655,151.

To all whom it may concern:

Be it known that I, JOHN C. McLAUGHLIN, a citizen of the United States, residing in Jersey City, in the county of Hudson and State of New Jersey, have invented 5 certain new and useful Improvements in Type-Writing Machines, of which the following is a specification.

This invention relates to typewriting machines, and especially to means for registering the amount of writing performed by an operator.

Heretofore, to register work, it has been customary to mount a cyclometer on the typewriter, so that its drive shaft or spindle was coupled directly to the axle of the escapement wheel. Figures were thus obtained from the register or cyclometer proportional to the amount of work done, from 20 which the actual work could be calculated. This manner of driving the cyclometer caused excessive pull on the escapement wheel axle, producing a heavy load on a type bar mechanism, which resulted in giving the keys a hard touch. The necessity for calculating also was objectionable. Moreover, it was not possible to attach the registers hitherto in use to tabulating machines, for the tabulating attachment usually is placed immediately behind the 30 escapement wheel, where such registers had to be located.

One object of my invention is to provide registering means whereby the load on the 35 type bar mechanism is greatly reduced, and thus prevent a hard touch.

Another object is to provide registering mechanism that can be attached to tabulating machines.

40 A still further object is to provide means for attaching the registering mechanism without making any alteration either in the typewriter or the mechanism, so that it can be easily attached or detached.

45 In carrying out my invention, a bracket or panel carrying the registering mechanism is strapped to the machine frame by means of a bar which can be screwed down. A gear having just as many teeth as the escapement wheel is mounted on said bracket, and a dog or pin on said gear is moved by 50 the escapement wheel as it rotates. Another gear wheel which will usually be larger, having as many teeth as there are

spaces on the platen scale, or letter spaces 55 in a line, is mounted on this panel, and driven by the first gear, so that a complete line of writing will turn the axle of this second gear once. The exact number of lines written then can be read off immediately, while the use of gearing such as I have described, greatly lessens the pull of the escapement axle. In case an ordinary cyclometer is used, where one turn of the shaft registers ten points, the units figure 60 65 may be neglected, and the actual number of full lines written will be represented by the other figures on the dials.

Other features and advantages will hereinafter appear.

70 In the accompanying drawings, Figure 1 represents so much of a section through an Underwood typewriter with my improvement attached, as is necessary to show its details. Fig. 2 is a view on an enlarged 75 scale, of the escapement wheel and gearing driven thereby.

Keys 1 are struck to depress levers 2 acting through bell cranks 3 to raise type bars 4 to strike type 5 against a platen 6. A universal bar 7 is actuated by heels 8 on type bars 4 whenever a key is struck, to move an escapement frame 9 pivoted at 10, and so move dogs 11 to control escapement wheel 12 and thus control the carriage of the typewriter in letter feeding movement. On the axle 13 of said escapement wheel, is the usual lock nut 14.

90 The machine so far described may be of any ordinary construction, and has been described in detail only to show how my improvement is applied to a given machine.

Attached to the frame of the machine by screws 15 and bar 16, is a panel 17 carrying the cyclometer or register and associated 95 gearing. This last comprises a gear wheel 18 having the same number of teeth as the escapement wheel 12, on which is mounted a pin or dog 19, which latter bears against and is rotated by the lock nut 14 of the escapement wheel in the letter-feeding motion of the typewriter carriage.

100 Meshing with the gear wheel 18 is a second gear 20, having the same number of teeth as there are letter spaces in a full line, and by the axle 21 of this wheel is driven a counting mechanism 22. This first gear is preferably mounted on a second panel

23 carried by the first panel 17. It will be apparent that very little power will be needed to drive the cyclometer, owing to the large reduction gearing employed. It is also evident that the writing of one full line will rotate the axle of the larger gear wheel axle once, thus making the units dial turn one full revolution in the usual types of cyclometers. The figures in the higher 10 places then will represent the aggregate number of full lines in the matter written, for the letter spaces in the incomplete lines are added in automatically as fractions of full lines during the progress of the writing. The gear wheels bring all projecting parts of the counting mechanism to one side of the tabulating mechanism as it is ordinarily placed, so as to be completely out of its way. It will also be observed that no 15 alterations need be made in the escapement wheel or in the frame of the machine to attach my registry mechanism and that only ordinary tools are needed. So my improvement can be attached by almost any one to 20 any ordinary typewriter in a few moments.

Variations may be resorted to within the scope of the invention, and portions of the improvements may be used without others.

The numerical relation between the number of teeth on the large wheel and the number of spaces on the scale, instead of being one of equality, as expressed above, merely, may be any suitable one of divisors or multiples.

35 Having thus described my invention, I claim:

1. The combination with a typewriter, of an escapement wheel, a gear wheel having the same number of teeth as the escapement 40 wheel, in free engagement therewith, a second gear wheel meshing with the first having the same number of teeth as there are letter spaces in a line, a registering mechanism driven by the axle of said second gear, and means turning said first wheel with the 45 escapement.

2. The combination with the escapement mechanism of a typewriting machine, of a counting register in mechanical connection 50 therewith, the gear wheel of the register

having the same number of teeth as there are places or space on the platen scale.

3. The combination in a typewriting mechanism, of an escapement wheel, a gear wheel in mechanical relation to said escapement wheel and connected to a counting mechanism, said gear wheel having teeth suitably numerically related to the number of spaces on the platen scale. 55

4. A registering mechanism comprising a gear wheel turning the counting wheels of the mechanism, the teeth in said gear wheel being in suitable numerical relation to the spaces in a line, a second gear meshing with the first, a pin on said second wheel to be 60 driven by a rotating member, a body carrying said gears and wheels, and means for attaching said mechanism to a typewriter.

5. The combination with a typewriter, of an escapement wheel, a gear wheel having the same number of teeth as the escapement, 70 a panel carrying said wheel, a gear wheel meshing with said first gear having the same number of teeth as there are letter spaces in a full line of writing, a counting mechanism, a panel carrying said first panel, said second gear and said counting mechanism, a bar, screws drawing said bar to coöperate with said second panel to grip the frame of the typewriter, and a pin on said first gear 75 to turn it with the escapement.

6. The combination with a typewriter, of an escapement wheel, an abutment on the axle of said wheel, a gear wheel having the same number of teeth as the escapement, a panel carrying said wheel, a gear wheel meshing with said first gear having the same number of teeth as there are letter 80 spaces in a full line of writing, a counting mechanism, a panel carrying said first panel, said second gear and said counting mechanism, a bar, screws drawing said bar to coöperate with said second panel to grip the frame of the typewriter, and a pin on said first gear to turn it with said abutment. 85
